UNITED STATES PATENT OFFICE.

JAMES H. EMERY, OF NEW YORK, N. Y.

ARTIFICIAL GRAPE AND METHOD OF PRODUCING SAME.

1,390,349.

Specification of Letters Patent. Patented Sept. 13, 1921.

Application filed February 5, 1921. Serial No. 442,603.

To all whom it may concern:

Be it known that I, JAMES H. EMERY, a citizen of the United States, residing at Inwood Park, county of Queens, city and State of New York, have invented new and useful Improvements in Artificial Grapes and Methods of Producing Same, of which the following is a specification.

This invention relates to artificial grapes and a method of producing such grapes.

The principal object of the invention is to produce artificial grapes which in appearance are substantially identical to the natural fruit.

A further object is to provide a simple, quick and economical method of producing such artificial fruit.

One embodiment of the invention is illustrated in the accompanying drawings in which:

Figure 1 is a diagrammatic front elevation of a mold for casting the cores of the grapes, showing the casting process in various stages,

Fig. 2 is a plan view of the mold shown in Fig. 1,

Fig. 3 is a vertical section taken on the line 3—3 of Fig. 2 and

Fig. 4 is a vertical section of a finished grape.

In carrying out the invention a two part mold of one or more natural grapes is first provided in any suitable manner, but most desirably in accordance with the method of

making such molds illustrated in the patent to applicant No. 1,373,121, granted March 29, 1921. The mold is then filled with a suitable quantity of any convenient or desired temporarily fluid thermoplastic com-

position. When the filling composition has cooled sufficiently to become viscous, a stem of suitable material, such as wire, is inserted to a proper depth in the mold. As cooling continues, the composition solidifies,

the stem becomes firmly embedded in the core, the mold is then separated and the core of the grape removed. Any bur or fin surrounding the stem is removed and the grape core is finished.

The core is now dipped in a molten bath of suitable thermoplastic material and immediately removed, sufficient of the bath material adhering to the core completely to coat the same. The coating hardens almost immediately after the core is removed from the

bath, and is then dusted with a suitable finely divided light colored powder, and the artificial grape is complete.

In the drawings 1 and 2 represent the co-operating parts of the mold, the part 2 being provided with a number of conveniently located studs 3 which fit into correspondingly located recesses 4 provided in the part 1 to insure correct registry between the parts 1 and 2. While the invention may be carried out with a mold for a single grape, it is most conveniently practised with a mold providing for the casting of say a dozen or more grapes at one operation. When such a mold is employed the upper inner edges of the parts 1 and 2 are beveled as at 5 to provide a trough for distributing the thermoplastic core material poured from the spout 6 to the various recesses 7. It is then only necessary while maintaining the upper edge of the mold substantially level, to pour the thermoplastic material into the trough whence it flows by gravity into the various recesses 7. Since most suitable thermoplastic materials have an appreciable coefficient of expansion upon heating and will therefore contract when cooled, it is desirable to pour a slight excess of the core composition into the trough. As this composition cools and shrinks in each individual mold 7, the excess material will flow from the trough into the recesses 7 thereby insuring a final casting of substantially the same size as that of the mold.

In producing imitations of grapes having a dark color, such as blue, it is immaterial whether the core is transparent or opaque, colored or colorless, since the outside coating 8 applied to the core will prevent the passage of light through the grape. When, however, grapes of a lighter color, such as light red or light green, are being imitated, it is important to use almost colorless and nearly transparent or at least translucent material in making the core. The remarkably close resemblance between the light colored artificial grapes produced in accordance with this invention and the natural articles results from the fact that the cores have substantially the same optical properties as the pulp of the natural grape, while the coating 8 has optical properties substantially identical to those of a natural grape skin.

In order to prevent the stem 9 from becoming detached from the core there is most

desirably provided a bent or hook portion 10 which, when embedded in the core, securely anchors the stem in place. Various materials are suitable for use as stems, but it has been found that the best results are obtained by the use of oxidized copper wire which possesses the necessary strength and flexibility and closely imitates the appearance of the natural stem.

10 In order to increase the resemblance between the artificial grape and the natural article and also to decrease the tendency of artificial grapes to adhere to one another in warm weather, it is desirable to dust the 15 coating with some adhesive powder of light color. The most satisfactory material for this purpose has been found to be finely divided oxid of zinc.

While the invention may be carried out 20 with various thermoplastic materials, such as animal, vegetable or mineral waxes, it has been found that the best results are obtained in casting the cores when a mixture of about 19 parts of paraffin to 1 part of carnauba 25 wax is used. The carnauba wax serves to raise the melting point of the mixture as well as to increase its hardness when in the solid state and the same mixture, with the addition of suitable coloring material, makes 30 the best coating for the grapes.

Having thus fully described the invention what is claimed is:

1. An artificial grape comprising a core of thermoplastic material and a coating of 35 colored material covering said core.

2. An artificial grape comprising a core of translucent thermoplastic material and a colored translucent coating covering said core.

40 3. An artificial grape comprising a core of colorless translucent wax and a coating of colored translucent wax covering said core.

45 4. An artificial grape comprising a core of colorless translucent wax, a coating of colored translucent wax covering said core

and a light colored powder adhering to the surface of said coating.

5. An artificial grape comprising a core of colorless translucent wax, a coating of 50 colored translucent wax covering said core and an oxid of zinc powder adhering to said coating.

6. An artificial grape comprising a core of thermoplastic material, a stem projecting 55 from said core, and a colored coating covering said core.

7. An artificial grape comprising a core of thermoplastic material and a stem projecting from the core, said stem having a 60 bent portion embedded within said core.

8. A core for artificial grapes comprising substantially nineteen parts of paraffin to one part of carnauba wax and having optical properties similar to those of a natural 65 grape pulp.

9. In an artificial grape, in combination, a core composed of material containing substantially nineteen parts of paraffin to one part of carnauba wax, and a colored coating 70 of the same material.

10. The method of producing artificial grapes which consists in filling a mold with a temporarily fluid thermoplastic material and allowing the contents of the mold to 75 cool until it becomes viscous, then inserting a stem in the viscous core, then allowing the contents to solidify, then removing the resulting core from the mold and coating it with colored thermoplastic material. 80

11. The method as claimed in claim 10 which consists in dusting the coating with powdered oxid of zinc.

12. An artificial grape comprising a core of thermoplastic material and a coating cov- 85 ering said core.

13. An artificial grape comprising a core of thermoplastic material and a stem projecting from the core, said stem having a portion embedded within said core.

JAMES H. EMERY.

DISCLAIMER

1,390,349.—*James H. Emery*, New York, N. Y. ARTIFICIAL GRAPE AND METHOD OF PRODUCING SAME. Patent dated September 13, 1921. Disclaimer filed December 23, 1933, by the patentee.

Hereby enters this disclaimer to claims 1, 2, 3, 4, 5, 6, 7, 12 and 13 of said Letters Patent, which are in the following words, to wit:

“1. An artificial grape comprising a core of thermoplastic material and a coating of colored material covering said core.

“2. An artificial grape comprising a core of translucent thermoplastic material and a colored translucent coating covering said core.

“3. An artificial grape comprising a core of colorless translucent wax and a coating of colored translucent wax covering said core.

“4. An artificial grape comprising a core of colorless translucent wax, a coating of colored translucent wax covering said core and a light colored powder adhering to the surface of said coating.

“5. An artificial grape comprising a core of colorless translucent wax, a coating of colored translucent wax covering said core and an oxid of zinc powder adhering to said coating.

“6. An artificial grape comprising a core of thermoplastic material, a stem projecting from said core, and a colored coating covering said core.

“7. An artificial grape comprising a core of thermoplastic material and a stem projecting from the core, said stem having a bent portion embedded within said core.”

“12. An artificial grape comprising a core of thermoplastic material and a coating covering said core.

“13. An artificial grape comprising a core of thermoplastic material and a stem projecting from the core, said stem having a portion embedded within said core.”
